US00D934281S

(12) **United States Design Patent** (10) Patent No.: **US D934,281 S**
Merrell et al. (45) Date of Patent: **** Oct. 26, 2021**

(54) **DISPLAY SCREEN WITH GRAPHICAL USER INTERFACE OR PORTION THEREOF**

(71) Applicant: **Google LLC**, Mountain View, CA (US)

(72) Inventors: **Paul Merrell**, Redwood City, CA (US); **Aaron Michael Donsbach**, Seattle, WA (US); **Vinay Damodar Shet**, Millbrae, CA (US); **Jonathan Siegel**, San Francisco, CA (US); **Julien Zachary Reneau-Wedeen**, Chicago, IL (US); **Andrew Kisielius Veritas**, San Francisco, CA (US); **Daniel Caleb Gordon**, Marietta, GA (US); **Su Chuin Leong**, Oakland, CA (US)

(73) Assignee: **GOOGLE LLC**, Mountain View, CA (US)

(**) Term: **15 Years**

(21) Appl. No.: **29/714,420**

(22) Filed: **Nov. 22, 2019**

- The ornamental design for a display screen with graphical user interface or portion thereof, as shown and described.
- DESCRIPTION**
- The present application is related to U.S. Design patent application Ser. No. 29/488,692, and to U.S. Design patent application Ser. No. 29/488,695, the entire disclosures of which are incorporated herein by reference.
- FIG. 1 is a front view of an image of a display screen with graphical user interface or portion thereof, according to a first embodiment of our design;
- FIG. 2 is a front view of an image of a display screen with graphical user interface or portion thereof, according to a second embodiment of our design;
